UNITED STATES PATENT OFFICE

132,668

DESIGN FOR A TIRE

Henry Franz, Newark, Ohio, assignor to The Pharis Tire and Rubber Company, Newark, Ohio, a corporation of Ohio

Application October 28, 1940, Serial No. 96,112

Term of patent 7 years

To all whom it may concern:

Be it known that I, Henry Franz, a citizen of the United States, residing at Newark, in the county of Licking and State of Ohio, have invented a new, original, and ornamental Design for a Tire, of which the following is a specification, reference being had to the accompanying drawing, forming a part thereof.

Fig. 1 is a perspective view of a tire, partly illustrated in dotted lines, showing my new design;

Fig. 2 is a transverse sectional view thereof taken on the plane indicated by the line II—II of Fig. 1, a part being cut away for convenience in illustration.

The distinguishing and characterizing features of the design consist in the configuration of the side wall and shoulder portions of the tire.

I claim:

The ornamental design for a tire, as shown and described.

HENRY FRANZ.
